ATTORNEY

UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

AIR PURIFIER.

Application filed October 19, 1926. Serial No. 142,619.

This invention relates to devices for separating foreign matter from a current of fluid, and more particularly adapted for application to a fluid pressure brake system.

5 With a fluid pressure brake system, a fluid compressor is installed on the locomotive and compresses fluid into one or more main reservoirs, from which fluid under pressure is supplied for controlling the brakes on the 10 train.

Oil and water are present in the fluid as compressed by the compressor, the oil being the lubricating oil used to lubricate the compressor and the water being that always present 15 in air taken from the atmosphere by the compressor.

It has been found that the oil and water in the air is liable to cause undesired action of certain valve devices employed in a fluid 20 pressure brake system, and for this reason it is desirable to separate the oil and water from the air compressed by the compressor before it is supplied to the fluid pressure brake system.

25 The oil and water tends to collect in the means for separating same from the current of air and then tends to clog the pipes through which air is supplied from the compressor to the storage reservoir and thus 30 interfere with the flow of air.

The principal object of my invention is to provide means for separating oil and water from a current of air and means operated when the separated oil and water tends to 35 clog the flow passages for supplying a liquid to said separating means for clearing same of the collected oil and water.

In the accompanying drawing; Fig. 1 is a diagrammatic view of an apparatus embodying my invention; and Fig. 2 a section 40 on the line 2-2 of Fig. 1.

In order to separate oil and water from a current of air, a plurality of vertically disposed sections 1 of coiled pipe are provided, the upper ends of the coiled pipe opening into a header 2, which is connected to an inlet pipe 3, through which air is supplied to the header. The lower ends of the pipe coils are connected to a drain reservoir 4, which 45 is provided with an outlet air pipe 5.

A receptacle 6 is provided which contains a liquid such as benzine which is adapted to liquefy a heavier oil, so that it will readily flow, and a liquid, such as alcohol, which is 50 adapted to liquefy frost which may be

formed from the water collecting in the separating means, when the apparatus is exposed to freezing temperatures.

The supply of liquid in the receptacle 6 to the separating means may be controlled by 60 a valve device comprising a casing 7 having a piston chamber 8 containing a piston 9. Said piston is adapted to operate a valve 10 for controlling the supply of liquid from the receptacle 6. A corrugated metal dia- 65 phragm 11 is attached to the piston 9 and forms a chamber 12 within which the valve 10 is disposed.

Chamber 12 is connected, through passage 13, past a check valve 14 and through pipe 70 15 with a distributing reservoir 16, said distributing reservoir having connected thereto a plurality of pipes 17, which lead to pockets 18 formed at the base of the header 2, each pocket being connected to one of the coiled 75 pipe sections 1.

For controlling the operation of the liquid supply valve device, a controlling valve device is provided, comprising a casing 19 containing a flexible diaphragm 20 adapted to operate a double beat valve 21. The chamber 22 at one side of diaphragm 20 is connected by pipe 23 to the air outlet pipe 5, and chamber 24 at the opposite side of the diaphragm is connected through pipe 25 with the header 2. 80 The valve chamber 26 containing the double beat valve 21 is connected through pipe 27 with piston chamber 8. The pipe 25 is also connected to the receptacle 6, so that the liquid in said receptacle is subject to the pressure of fluid supplied to the header 2. 85

In operation, air or fluid under pressure supplied to pipe 3 flows into the header 2 and thence through the coiled pipe sections 1 to the drain reservoir 4. Oil and water which may be held in suspension in the current of air passing through the coils, collects on the inner walls of the pipe coils, so that the air which flows to the reservoir 4 is freed of oil and water and thence flows out through 100 the outlet pipe 5 to the fluid pressure brake system.

So long as there is a free flow of fluid through the coiled pipe sections, the inlet pressure of fluid supplied through pipe 105 25 to one side of diaphragm 20 will be substantially equal to the outlet pressure of fluid supplied through pipe 23 to the opposite side of diaphragm 20, so that the spring 28 acts through the diaphragm 110

20 to hold the double beat valve 21 to its upper seat, as shown in the drawing, in which position, piston chamber 8 is connected at atmospheric exhaust port 29. The 5 spring 30, acting on piston 9 then moves the piston, so that valve 10 is unseated, permitting liquid from the receptacle 6 to flow to chamber 12. The liquid in the receptacle 6 is subject to the pressure of fluid in the 10 header 2 as supplied through pipe 25, and since the fluid pressure in the reservoir 16 and in pipe 15 is the same as that in the header, there will be no flow of liquid to the pipe 16.

15 If the pipe coil sections 1 should become clogged with oil and water, so as to impede the free flow of fluid from the header 2 to the reservoir 4, then the pressure of fluid in the header 2 will exceed that in the reservoir 20 4, and consequently the fluid pressure in diaphragm chamber 24 will exceed that in diaphragm chamber 22. As a result, the diaphragm 20 will be moved downwardly, so that the double beat valve 21 seats in the 25 lower position, cutting off communication from piston chamber 8 to the atmospheric exhaust port 29 and opening communication from chamber 22 and pipe 23 to said piston chamber.

30 Fluid under pressure from the outlet pipe 5 is thus supplied to piston chamber 8, and thereby the piston 9 is moved upwardly, the area of the piston 9 exposed to the inlet fluid pressure in chamber 12 being less than 35 the area of the piston which is exposed to the outlet pressure.

The upper movement of piston 9 closes the valve 10 and forces the liquid in chamber 12, past the check valve 14 and through 40 pipe 15 to the reservoir 16. Thence the liquid is distributed to the several cups 18 and flows into the corresponding pipe coil sections 1. Liquid so supplied acts to 45 liquefy the oil collected in the coils, so that it will drain out of the coils into the drain reservoir 4.

If the coils are subject to freezing temperatures, the liquid may contain alcohol or other agent adapted to liquefy frost formed 50 by the water which collects in the coils.

A drain cock 31 may be applied to the drain reservoir 4, so that by operating the cock, liquid collected in the reservoir may be drained out.

55 With the construction above described, the amount of liquid supplied is fixed and limited to the amount of liquid which is forced out by the upward movement of the piston 9, and after the piston 9 has moved 60 to its extreme upward position, no more liquid will be supplied, even though the diaphragm 20 should continue to hold the double beat valve 21 in its lower position. Consequently, an excessive amount of liquid

will not be supplied to the separating means. 65

Having now described my invention, what I claim as new and desire to secure by Letters Patent, is:—

1. The combination with separating means interposed in a stream of fluid for collecting 70 oil and water contained in said stream, of a piston operated by fluid under pressure for forcing a liquid into said means, which acts to clear said means of the collected oil and water, and means subject to the opposing 75 pressures of the fluid inlet and outlet of said separating means for controlling the supply of fluid under pressure to said piston.

2. The combination with separating means interposed in a stream of fluid for collecting 80 oil and water contained in said stream, of a piston operated by fluid under pressure for forcing a liquid into said means for clearing said means of the collected oil and water, a valve operated by said piston for 85 controlling the supply of liquid to said piston, and means controlled by the opposing pressures of the fluid inlet and outlet of said separating means for controlling the fluid pressure on said piston. 90

3. The combination with separating means interposed in a stream of fluid for collecting 95 oil and water contained in said stream, of a piston operated by fluid under pressure for forcing a liquid into said means for clearing said means of the collected oil and water, a valve operated by said piston for 100 controlling the supply of liquid to said piston, a diaphragm subject to the opposing pressures of the fluid inlet and outlet of said separating means, and a double beat valve operated by said diaphragm and having one position for supplying fluid under pressure to said piston and another position in which said piston is connected to the 105 atmosphere.

4. The combination with separating means interposed in a current of fluid for collecting 110 oil and water contained in said current, of means operated upon the clogging of said separating means with oil and water for supplying a fixed predetermined amount of liquid to said separating means, the liquid so supplied being adapted to clear said separating means of oil and water. 115

5. The combination with separating means interposed in a current of fluid for collecting 120 oil and water contained in said current, of means operated upon the clogging of said separating means with oil and water for supplying a fixed constant amount of liquid to said separating means, the liquid so supplied being adapted to clear said separating means of oil and water.

In testimony whereof I have hereunto set 125 my hand.

CLYDE C. FARMER.
